PHONOGRAPH CONTROL

Clifford H. Green, Grand Rapids, Mich., assignor
to Automatic Musical Instrument Company,
Grand Rapids, Mich., a corporation of Michigan

Application February 5, 1934, Serial No. 709,691

2 Claims. (CL 274—10)

This invention relates to improvements in automatic phonograph apparatus, and more particularly to the provision of remotely controlled apparatus so that the operation, selection of records, cancelling of the selections and changes in the program may be controlled from a distance, and the different parts of the apparatus may be located in the most suitable place for the specific part.

For example in homes, it may be desirable to place the sound reproducer or loud speaker in different rooms, or on a wall, where there are no places adjacent the desirable location of the speaker for the rest of the apparatus. Also it is desirable to be able to control the music from different locations which may be changed at will; and accordingly objects of this invention include the provision of a readily portable control unit, which occupies little space and is easy to carry about.

Further objects of the invention are to provide automatic phonograph equipment which is suitable for such use as in theaters where it is necessary to control the program from behind the audience or in the operating room where the phonograph instrument would be in the way, it of course being necessary to place the sound reproducer instrument in front of the audience or on the stage.

Further objects and advantages will become apparent in the following description, taken with reference to the accompanying drawings, in which:

Fig. 1 is a representation of the several differently located interconnected units of the apparatus.

Fig. 2 is a diagram of the electrical remote arrangement.

Fig. 3 is a plan view of a preferred form of the phonograph instrument, which is more fully shown and described in my co-pending application, Serial Number 712,218, filed Feb. 20, 1934, and therefore need not be completely shown and described herein, except as to essential details, since the invention may be carried out with other specific phonograph mechanism.

The phonograph instrument mechanism shown in its entirety in Fig. 3 comprises, essentially, a horizontal turntable A; a stylus B; a magazine C for record discs D; a transfer mechanism E for removing records from the magazine, placing them on the turntable, and then restoring the record to the magazine; and a selector mechanism F for bringing the magazine and transfer

into cooperative relation for selecting the desired records.

The turntable is rotated by a motor 1 which is controlled by a mercury bulb starting switch 2; and the selector and transfer mechanisms are driven by the transfer motor 3 which is controlled by a mercury bulb switch 4, through and under the control of the switch 2, so that the transfer mechanism may be stopped while a record is being played to eliminate the noise and vibration of the idling parts.

The electrical connections for accomplishing this are shown diagrammatically in Fig. 2, in which lines 5 and 6 represent a 110 volt supply circuit, across which is connected a primary 15 transformer winding 7 which energizes a secondary winding 8 at about 10 volts for operating the control circuits, as will be described hereinafter.

One terminal of each of the motors 1 and 3 is connected by conductor 9 to the supply wire 5; 20 and the opposite supply wire 6 is connected by line 10 to one terminal of the switch 2. The switch 2 is normally held in open position by a latch 11 against the pull of a spring 12; and the opposite terminal of the switch 2 is connected 25 directly to the second terminal of the turntable motor 1 by wire 13, and to the switch 4 by wire 14, thence through the switch 4, when closed, and to the transfer motor 3 by line 15. The transfer motor switch 4 is normally held in closed position by a spring 16. Thus closing the switch 2 immediately starts both motors, opening switch 4 stops the transfer motor, which is done while the record is being played. Then closing the switch 4 again starts the transfer motor to remove the disc; and finally opening of switch 2 30 stops both motors to leave the apparatus in normal condition.

The motor 3 is belted to a drive shaft 17, Fig. 3, which is connected through a normally closed selector and magazine drive clutch mechanism represented by lever 18 to drive a stop lug selector drum 19, included in the selector mechanism, and, simultaneously to move the magazine C, slidably mounted on rods 20, 21, back and forth 45 in relation to the transfer mechanism. As will be understood, all of this mechanism is more fully shown and described in said co-pending application, and the description herein is limited as much as possible to essential features particularly 50 related to this invention, and to the manner of operation.

Thus when the transfer motor is started, from normal condition of the parts, the selector drum 19 is rotated in synchronism with the reciprocating 55

ing movement of the carriage D, the carriage moving to the right during the first half of the revolution of the drum, and back to the left during the second half. In the drawings the carriage is shown in mid-position so that an intermediate disc is presented to the transfer, and the magazine may be moved in the same direction, when again connected by the clutch 18 to the shaft 17 and transfer motor, to finish the un-
10 completed reciprocation.

At the end of each reciprocation the transfer is conditioned by means of stops 22 and 23, mounted on the carriage, as shown in said application, to reverse the direction of the ninety degree turning of the transfer pick-up arm 24 as the selected record is being placed on the turntable.

Accordingly the records on one side of the discs are presented in playing position during movement of the carriage in one direction, and the other sides of the records are presented during the return movements, making it possible to select any of the records carried on the discs.

A pair of clutches 25 and 26 are provided for connecting the motor driven shaft 17 to a transfer jack shaft 27 which is positively connected to position the tone arm B and operate the transfer E to place the selected record either on the turntable or, with a reverse movement, back into the magazine. The movement of the shaft 27 is limited to less than one complete rotation from normal position so that, in moving from normal position, the record then opposite the transfer, is gripped, lifted out of the magazine, turned according to the last movement of the carriage, and deposited on the turntable and released. Then in the final movement of the shaft the stylus B is swung over the record and lowered to engage in the outer grooves of the record, 40 which then swing the stylus in towards the center of the turntable. After the record is played, the movement of the shaft 27 is reversed, as will be briefly described, and the record and stylus restored to normal position.

45 The clutches 25 and 26 are operated in alternate relation by a longitudinally movable clutch operating rod 30 which is moved by a centrally pivoted lever 31, the lower end of which is pivotally connected to the main operating bar 32, which is one of the principal control elements. The movements of the clutch rod 30 are indicated by center lines in Fig. 2, designated N for neutral position, F for forward position to present a record on the turntable, and R for reverse to 50 remove and restore the record.

When the bar 32 is moved to the left and the rod 30 thereby moved to the right, the clutch 26 is operated to connect a bevel pinion 33 to the shaft 17. In neutral position of the rod 30, both 55 clutches are released; and when the rod 30 is moved to the left, by a movement to the right of the bar 32, the clutch 25 is engaged to attach the bevel pinion 34 to the shaft 17. The two pinions mesh oppositely with a bevel gear 35 for rotation of the same in either of the two directions; and the gear 35 is positively connected to the shaft 27 through a worm gear 36, keyed on said shaft. A bifurcated lever 37, pivoted at 38, is pivotally connected to the shifter rod 30, and the 60 arms 39 of the lever 37 loosely embrace the edge of the gear 36 on the sides of which are provided two spaced cam lugs 40. The lugs 40 are radially disposed in staggered relation on the opposite sides of the gear 36 and project so that they 65 move the lever 37, and shifter rod 30, to neutral

position whenever they come into contact with the corresponding arm 39. This arrangement limits the rotation of the shaft 27 to less than one complete turn, and automatically moves the shifter rod back to neutral position to release either clutch 25 or 26 when either movement is completed. The construction of said clutches is such that the actual clutch movement is effected by power from the drive shaft 17, as described in said application.

10 The remaining electrical control units which are mounted in the phonograph instrument are a plurality of selector solenoids 40, one for each record; a solenoid 41 for stopping the playing of a record; a solenoid 42 for cancelling the selections which have been set up but not yet cancelled by the playing of a record; and a switch 43 which is closed by the stylus when the playing of a record is completed.

15 A portable control board 44 is provided, which may be placed on a table 45, or in any other convenient location at a distance from the phonograph cabinet 46 in which the phonograph instrument is mounted and connected to the remote control board by a cable 47. A loud speaker unit 48, electrically connected to the stylus, may be mounted in the phonograph cabinet, or mounted in a remotely positioned housing, such as a cabinet 49, indicated in broken lines in Fig. 1.

20 In the control board is mounted a row of manually operable selector push buttons 50, a push button 51 for stopping the playing of a record; and a push button 52 for clearing the selections so that a program which has been set up by pressing several of the selector push buttons may be discontinued or altered as may be desired.

25 The low voltage power for energizing the control circuits is supplied from the secondary winding 8 which has a return feed wire 53 which extends through the cable 47 and is connected to the one contact finger 54 of each of said push buttons. The second contact fingers 55 of the selector push buttons 50 are each connected to one terminal 56 of the solenoids 40 which correspond to the same records as the push buttons, by wires 57 which are bunched and passed through the cable 47.

30 One terminal of the stop switch 43 is connected by wire 61 to lead 53; and one terminal of the stopping solenoid 41, the selector solenoids 40, and the clearing solenoid 42 are each connected to the feed wire 60, of the transformer 8, by the wires 62, 40a, and branch wire 63, respectively. The second terminal of the solenoid 42 is connected through the cable 47 by a wire 64 which leads to contact finger 65 of the push button 52; and the second terminals of the switch 43 and solenoid 41 are joined by wire 66 which is connected, through the cable 47, by wire 67, to the contact finger 68 of the push button 51.

35 The selector F comprises, in addition to the group of solenoids 40 and the drum 19, a bank of selector levers 69 and latches 70, one lever and one cooperating latch being associated with each of the solenoids 40. The levers 69 are mounted on downwardly movable pivots 70a, and are guided at their upper ends in slots provided in a fixedly mounted comb 71. Normally the levers 69 are latched in position away from the drum 19 by engagement in a notch 72 in the corresponding latch 70, the latches and levers being urged into engaging relation by an interconnecting spring 73. When a solenoid 40 is energized the 40

latch 70 related therewith is drawn back to release its lever 69 which is then rotated clockwise so that angular point 74 thereof is in close relation with the surface of the drum. This movement of each lever about its pivot 70a rotates a universal bar 75 clockwise about its shaft 76 and closes the starting switch 2. As described in said application, this movement of the bar 75 raises a slide 77 which lifts and holds the latch lever 11 10 out of engaging relation with the switch 2, and allows the spring 12 to close the switch and start the two motors. This starts the coordinated movement of the magazine and drum.

On the drum are provided a plurality of lugs 15 78 individually corresponding with the selector levers 69, and consequently with the records in the magazine. The lugs are arranged helically on the surface of the drum so that one lug after another is moved into cooperative relation with 20 its lever in timed relation with the movement of the carriage so that when a released lever is reached the disc having the selected record thereon is opposite the transfer.

The lug then presses the released lever down- 25 wardly until the comb 71 cams the lever away from the lug. This movement of any of the levers 69 rotates the universal bar 80 counterclockwise about the pivot 81 thereof. The bar 80 is positively connected to the control bar 32, and this 30 movement pulls the bar 32 to the left which moves the shifter rod 30 to the right to engage the clutch 26, and also, through a centrally pivoted lever 82 which is pivotally connected to the bar 32, releases the clutch 18. This movement of bar 80 35 stops the motion of the drum and carriage, and starts the operation of the transfer which is described above by rotating the shaft 29 away from normal position.

The clutch 18 is operated to engage by a cam, 40 not shown, which is positively connected to shaft 27 and rotates therewith, so that as soon as the shaft 27 is moved from normal position the clutch 18 is free for being released by the movement of the bar 32; and when the shaft 27 is moved back 45 to the normal position the clutch is restored to engaging condition.

The selector levers 69 are restored by being 50 pressed downwardly by the contacting lug on the drum until the angular surface below the point 74 in bearing against the forward edge of the slot in the comb 71, forces the point back until it clears the lug. The lever is then free to be drawn upwardly by the spring 73 until the lever engages the upper side of the notch 72, which 55 straightens and places the lever in normal position. The resulting movement of the bar 32 trips the clutch 18 which is finally released by the first movement of the transfer shaft 27 as fully explained in said application.

60 Thereupon, if none of the other levers 69 have been released, the universal bar 75 rotates back with the movement of the restored lever 69, to normal position. By the return movement of the bar 69, the slide 77 is lowered so that the latch lever 11, in moving to the right, will engage with the switch 2 and restore the same to the normal open position, and thus stop the operation of the motors.

However, if other levers 69, are still released, the 70 bar 75 will remain rotated to the right and the slide 77 will be held up to prevent the engagement of the latch 11 with the switch 2. Then the drum will be further rotated, as soon as the transfer has completed its return movement and the 75 clutch 18 is reengaged.

When it is desired to play any one of the records carried on the discs stored in the magazine, the corresponding push button 50 is pressed, and may be instantly released, giving a momentary energization of the corresponding solenoid 40, 5 from transformer line 53, push button 50, wire 57, winding of solenoid 40, common return lead 40a, to the opposite line 60 of the transformer secondary 8.

This, to follow the operation through completely, pulls the latch 70 out of engagement with the lever 69 which is then rotated about its pivot 70a so that the point 74 will project into the path of the corresponding lug 78. This movement of lever 69, under the action of the spring 73, 15 presses the plate 75 back and rotates its shaft 76 clockwise. The shaft 76 is pivotally connected by crank arm 83 to slide 77, and thereby lifts the lever 11 to release the switch bulb 2 so that the switch is swung by spring 12 to a vertical position in which the switch is closed, and so remains as long as any one of the selector levers 69 are released. This closing of switch 2 energizes the motor 1, from line 5, wire 9, through the motor, through wire 13, through the starting switch 2, wire 10 to opposite line wire 6; and the transfer motor 3 is energized from wire 9, 20 motor, wire 15, through the closed switch 4, wire 14, closed switch 2, to return wire 10, and line wire 6. 25

The motor 3 then rotates the drum and correspondingly drives the carriage through the closed clutch 18. When the lug 78 contacts and operates the released selector lever, as described, the plate 80 is momentarily depressed and its shaft 81 rotated slightly counterclockwise, and thereupon moves the crank arm 84, fixedly mounted on the shaft 81, and the bar 32 to the left, and the shifter rod 30 to the right from 30 neutral position N to forward position F. 40

This movement of shaft 81, through another crank arm 85, also moves a latch lever 86 to the left so that its tooth 87 is in position to engage with the switch 4 on the next movement of the lever 86 to the right, or when the clutch shifter 45 30 is returned to neutral position.

With the shifter rod 30 in forward position, the shaft 26 is rotated to deposit a record on the turntable. The transfer operation is completed by slightly less than one full turn of the shaft 50 27, and spaced lugs 90 or 91 automatically move the rod 30 back to neutral position at the completion of the movement of the shaft 27 in either direction, the lugs moving into contact with corresponding arms of a bifurcated lever 92 which is 55 pivoted at 93 and pivotally connected to rod 30.

Thus when the forward transfer movement is completed, and the rod 30 restored to neutral, the bar 32 is moved back to the right. In this return from forward to neutral, the lever 11 does 60 not move back far enough to re-engage the switch 2; but the lever 86, in moving back to neutral, rotates the switch 4, against the action of the spring 16, to open position, and thus stops the operation of the transfer motor while the 65 record is being played.

In the forward movement of the transfer shaft 27, the stylus was swung over, freed, and lowered into engagement with the outer grooves of the record, and the rotation of the turntable then 70 moves the stylus toward the center of the record. When near the center, the stylus arm contacts with the edge of an upstanding plate 94, secured to one of the contact fingers of the switch 43, and momentarily closes the switch. 75

This closes a circuit through the solenoid 41; from line 53, wire 61, switch 43, wire 66, solenoid 41, wire 62 to opposite line wire 60.

Energizing the solenoid 41 moves the bar 32 to the right, shifting the clutch rod, and the entire system of links and levers, to reverse position R, moving levers 11 and 86 to the right from the neutral position shown.

The reversed movement of the shaft 27 then removes the stylus, placing it again in normal position as shown in Fig. 3, and restores the record to the magazine, the transfer motor switch 4 having been released to return to closed position. In the movement to the extreme right, the lever 86 is cammed upward by a fixed plate 95 to release the switch from the tooth 81. The lever 11 is moved back to engage and open the switch 2 on again returning to neutral position when the record is restored. This is effected by the lug 91 striking the left arm of the lever 92 when the return or reverse transfer movement is completed and moving the clutch shifter train of parts back to normal position.

Thus all parts are restored to normal condition, unless the switch 2 is held open by a released selector lever 68 which has not been restored. In that case the movements are repeated to play all of the selected records, one after another; until all of the selector levers have been restored.

If desired, the playing of a record may be stopped by pressing the remote control push button 51. This closes a circuit from line 53, push button contact 54 to 68, wire 67 (shunting around switch 43), wire 66, solenoid 41, wire 62, to the opposite transformer lead 60. This moves the shifter rod 30 from neutral to reverse, starts the transfer motor to remove the stylus and return the record to the magazine.

Any or all of the waiting released selector levers 68 may be restored, and the selections cancelled, by pressing the clearing push button 52 which closes a circuit from transformer lead 53, contact 54, to contact 65, wire 64, solenoid 42, wires 63 and 62 to the opposite transformer lead 60. A U-shaped bar 95' is pivotally mounted on pins 96, only one of which is shown in the diagram, and the bar extends along in front of upwardly projecting fingers 97 provided on each of the selector levers 68, so that when the bar 95 is moved clockwise about the pivots 96, the fingers

97 will be pressed back to the normal position shown, and the levers re-engaged in the notches 12 in the corresponding latch members 10. The bar 95 has an arm 98 which projects above the pivot 96, to which one end of a bar 99 is pivotally connected. The bar 99 has a notch 100 in which the upper end of an oscillating lever 101 is engaged when the solenoid 42 is energized, as described, the bar 99 being normally held out of engagement with the lever 101 by a spring 99a. The lever 101 is oscillated by a cam 103 on a shaft 102 which is connected by the clutch 18 to the drive shaft 17. Thus the selections may be cancelled during the selector movements.

Having thus described my invention, I claim: 15

1. In an automatic multiple record phonograph means for selecting any of the records to be played, comprising a normally restrained lever for each record, a universal bar associated with the levers as a group for restoring any and all of the levers to normal position, means for operating the universal bar comprising an attached bar having a notch therein, a motor driven shaft, an arm reciprocated by the shaft having an extremity to engage the notch in the bar and remote control electrical means for actuating the bar to draw its notch into engagement with the arm for reciprocating the bar and the universal bar connected thereto for restoring the levers to normal position. 25

2. In an automatic multiple record phonograph, means for selecting a number of records to be played in succession comprising a releasable lever for each record, remote control means for actuating a driving motor to withdraw, play, and return a record after it has been played, and remote control manual means for cancelling the selections to be played at any time before all the previously selected records are played, said means comprising a universal bar mounted adjacent the levers for restoring the selected ones to normal position, a motor driven shaft having an eccentric thereon, an arm reciprocated by the eccentric, a notched bar connected to the universal bar and supported with its notch out of engagement with the said arm and a remote control solenoid for actuating the notched bar to bring its notch into a position to engage the end of the arm, thereby cancelling any and all remaining selections by returning the selected levers to normal position. 40 45

CLIFFORD H. GREEN. 50
